CLAIM

The ornamental design for a dual motor transom bracket for pontoon boats, as shown and described.

DESCRIPTION

FIG. 1 is a front top left side perspective view of the dual motor transom bracket for pontoon boats.

FIG. 2 is a back side perspective view of the dual motor transom bracket for pontoon boats.

FIG. 3 is front view of the dual motor transom bracket for pontoon boats.

FIG. 4 is a back view of the dual motor transom bracket for pontoon boats.

FIG. 5 is top view of the dual motor transom bracket for pontoon boats.

FIG. 6 is a bottom view of the dual motor transom bracket for pontoon boats.

FIG. 7 is a left side view of the dual motor transom bracket for pontoon boats.

FIG. 8 is a right side view of the dual motor transom bracket for pontoon boats.

FIG. 9 is a front perspective view of the dual motor transom bracket for pontoon boats which is attached to a pontoon boat; and,

FIG. 10 is a front perspective view of the dual motor transom bracket for pontoon boats which is attached to a pontoon boat and with dual outboard motors being attached thereto. The subject matter shown in broken lines is environmental background and does not constitute any part of the claimed design. The dot-dash lines in FIGS. 9 and 10 illustrate the boundaries of the dual motor transom bracket for pontoon boats attached to a pontoon boat with dual outboard motors and form no part of the claimed design.
